(57) **CLAIM**

The ornamental design for a set of car pedals, as shown and described.

DESCRIPTION

FIG. 1 is a front perspective view of a brake pedal of a set of car pedals showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of an accelerator pedal of the set of car pedals showing my new design;

FIG. 10 is a rear perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The brake foot pedal and accelerator pedal shown in FIGS. 1-16 collectively form the set of car pedals.
